TACKING MACHINE

Alfred John Batten, Brentford, England, assignor
to Gerrard Industries Limited, Brentford,
England

Application January 11, 1949, Serial No. 70,289
In Great Britain January 22, 1948

4 Claims. (Cl. 1-49)

1

This invention relates to stapling machines of the kind in which staples in strip form are fed from a magazine and are sheared off and driven home by means of a spring actuated hammer.

A stapling machine of the above kind according to the invention has a body part and a manually operable handle pivoted to the body part, movement in one direction of the handle serving to compress the hammer actuating spring and later to release a trigger lever itself pivoted to the handle and movement in the other direction serving to re-engage the trigger lever with a combined hammer and shearing blade by which the actuating spring is compressed on the next movement of the handle.

The trigger lever works in a slot in the body of the machine and has a cam portion cooperating with a pin fixed transversely across the slot to effect disengagement from the hammer when the actuating spring is fully compressed. A double torsion spring coiled about the pivot of the trigger lever serves the double purpose of pressing the trigger into engagement with the hammer and returning the handle of the machine after operative movement is complete.

The body of the machine is preferably made of a light alloy and has a slot for the operator's fingers. The magazine for the strip of staples is a plain rectangular section open slot in the base of the body and keyed grooves are provided in the body for the reception of a sliding cover which may be a steel pressing, said cover enclosing both the magazine and the hammer operating mechanism.

The handle of the machine may be another steel pressing which fits over the body part so as to avoid lost movement as the handle and body part come together on the operative stroke of the handle.

Other features of the invention include the provision of a separate hardened steel anvil piece fixed to the magazine cover by a screw or screws for use with staples; separable hammer and shearing blade pieces so as to provide for using staples of different widths by using blades of different widths; and the provision of a bayonet type cap for simple closure of the magazine slot.

The novel features that are considered characteristic of the invention are set forth with particularity in the appended claims. The invention itself, however, both as to its organization and its method of operation, together with additional objects and advantages thereof, will best be understood from the following descrip-

2

tion of a specific embodiment when read in connection with the accompanying drawing, wherein like reference characters indicate like parts throughout the several figures and in which:

5 Fig. 1 is a side view, partially in section, of a machine embodying the present invention;

Fig. 2 is a cross-sectional view taken on the line II-II of Fig. 1, and

Fig. 3 is a rear perspective view of the machine

10 cover.

Referring specifically to the drawing, a machine in accordance with the present invention comprises a light alloy body 1 with a suitably shaped aperture 2 for the fingers of the operator, so that the upper part of the body can be conveniently gripped. The base of the body is provided with a rectangular section open slot 3 for the reception of a strip of partly separated or separate adhesive joined staples S. A light coil spring 6 working in the slot 3 urges the staples forward in the slot towards the front of the body. The strips of staples are fed into the rear end of the magazine slot and are urged forward by the compression spring 6. The rear end of the magazine slot is closed by a removably seated bayonet type plug or cap 26.

15 The front of the body has a face 21 perpendicular to the base, and this face is slotted to form a guide and enclosure for the combined hammer and shearing blade and the actuating spring. A rather deep slot 28 opens through the top of the body and extends to a dead end at the base and this slot forms a guide for the hammer 8 and an enclosure for the actuating spring 9 which bears on the hammer 8. A shallow slot 27 extends from the dead end of the slot 28 through the body base and forms a guide for the shearing or driving blade 7. A narrow slot 10 extending from the rear of the slot 28 and through the height 20 of the body 1 accommodates and guides a trigger lever 12.

25 A hard steel pin 11 is fitted transversely across the slot 10 towards the front of its upper end. This pin serves as an abutment or cam to withdraw the trigger lever 12 from engagement with the hammer 8 and thereby release the hammer and shearing blade to the influence of the spring 9. A pressed hollow actuating lever or handle 13 is pivoted to the upper part of the body by a pivot 30 14 which is located at a distance from the front face 21 of the body equal to about one-third of the overall length of the body.

35 A second pivot pin 15 is carried by the handle 13 and is located approximately halfway between the main pivot 14 and the forward end of the

handle. This pin carries the trigger lever 12 and torsional spring 16, the ends of which are compressed against the underside of the handle and the back of the trigger lever. The effect of this spring is to urge the trigger lever toward the hammer 8 and against the hard steel pin 11 and to urge the operative end of the handle 13 away from the body.

The trigger lever has a hook 17 for engagement with a notch 18 in the rear face of the hammer 8. The underside of the hook is curved to facilitate this engagement. Above the hook, the trigger lever has a cam part or projection 19 which engages the hard steel pin 11 to effect disengagement of the hook from the hammer and shearing blade after the latter has been raised a predetermined distance by the hook 17 on a closing movement of the handle.

The hammer and shearing blade may be formed as a single piece from hardened steel or may be constructed to be separable. In the latter case the shearing blade 7 may be removably attached, as by one or more countersunk screws 29 or the like, to the hammer 8. By the latter construction, blades 7 of different widths may be selectively installed to deal with staples of different widths; and shims or packing pieces may be used as and where necessary.

Keyed grooves or the like 4 are provided in the longitudinal sides of the body for the reception of the magazine cover 5b of a combined magazine and front cover 5 which may be slid in from the front of the machine and may be held in position by pins 25 passing transversely through the body above the magazine slot 3. In addition to the magazine cover 5b, the cover 5 also comprises a front cover portion 5a which fits over the front face 21 of the body 1 and encloses the shearing blade slot 27 and hammer slot 28, the front wall of the front cover 5a forming the front guide surface for the blade 7 and hammer 8.

The front cover 5a terminates in a top part 5' which covers the open upper end of the hammer slot 28, said top part 5' having an opening for passage of the actuating spring 9. This top part opening is closed by a removably seated bayonet plug or cap 20 that also compresses the spring 9 down on the top of the hammer 8. Thus, if the actuating spring 9 jams or breaks it is readily accessible by removal of the cap 20.

A small slot 23 is provided in the forward end of the base of the cover 5 for passage of a staple S and the shearing blade 7, and a hardened steel anvil piece 24 may be removably secured to the inside of the cover with its shearing edge in line with the rear face of the slot 23. This anvil piece 24 may be replaced by a piece slightly shorter or longer, or it may be provided with a slot for adjustment so that its edge may be brought into the correct operative relationship with a wider or narrower shearing blade 7.

The operation of the machine is as follows: The bayonet plug or cap 26 at the rear end of the magazine slot 3 is removed and a strip of staples S is fed in. The light compression spring 6 is fed in behind them and the cap 26 is replaced. The foremost staple is now held with its forward edge bearing against the back of the shearing blade 7 and moves into operative position against the inside of the front cover plate 5a as the blade is lifted for an operative stroke.

The machine is held in position with its lower forward edge resting on the work-piece into

which the staple is to be driven. The hand lever 13 is then depressed, compressing the actuating spring 9 by lifting of the hammer 8 through the engagement of the trigger hook 17 with the hammer notch 18.

Further depression of the handle 13 raises the trigger lever 12 until the cam part 19 engages the hard steel pin 11 which cams the trigger rearwardly, releasing the hook from the notch and allowing the hammer and shearing blade to be driven forcibly down by the expansion of the actuating spring. The hand lever is then permitted to return under the influence of the torsional spring 16 on the trigger lever pivot, and towards the end of its return stroke the hook part of the trigger lever (which is curved on the underside) re-engages the recess in the rear face of the hammer and shearing blade combination.

Thereafter the staples will be successively driven home for each depression of the hand lever until the magazine is exhausted.

In the case of any fault or jam in the magazine or other part, the whole interior and working parts can be immediately made available by removal of the pins 25 and withdrawal of the combined magazine and front cover plate.

Although a certain specific embodiment of the invention has been shown and described, it is obvious that many modifications thereof are possible. The invention, therefore, is not to be restricted except in so far as is necessitated by the prior art and by the spirit of the appended claims.

I claim:

1. In a stapling machine of the type including a body portion having a staple magazine in the bottom part and an actuating mechanism including a hammer and shearing blade assembly in the front part, and a spring-retained manually operable handle movably mounted on the body portion for operating said actuating mechanism, the improvement comprising a unitary cover member having front and bottom portions for covering both the front and bottom parts of said body portion, said cover member being removable forwardly from the body portion to expose the actuating mechanism and staple magazine.

2. A machine according to claim 1 wherein a hard steel anvil piece is fixed on said bottom cover for cooperation with the shearing blade to facilitate the shearing action.

3. A machine according to claim 1 wherein the shearing blade is removably attached to the hammer.

4. A machine according to claim 1 wherein said hammer and blade-actuating spring is compressed between said hammer and the top part of the front portion of the cover member, said top part having an opening for the passage of said spring, and a removable closure for said opening and forming a seat for compressing said spring against the hammer.

ALFRED JOHN BATTEN.
